[57] CLAIM

The ornamental design for a golf club putter head, sub-
stantially as shown and described.

DESCRIPTION

FIG. 1 is a front perspective view of a golf club putter
head embodying my new design;
FIG. 2 is a right side elevational view thereof;
FIG. 3 is a rear elevational view thereof;
FIG. 4 is a top plan view thereof; and
FIG. 5 is a bottom plan view thereof.
